UNITED STATES PATENT OFFICE.

OSCAR J. MARTINSON, OF CHICAGO, ILLINOIS, ASSIGNOR TO MONIGHAN MACHINE CO.,
A CORPORATION OF ILLINOIS.

EXCAVATOR-TRACTOR.

1,101,460.

Specification of Letters Patent. Patented June 23, 1914.

Application filed April 5, 1913. Serial No. 759,240.

To all whom it may concern:

Be it known that I, OSCAR J. MARTINSON, a citizen of the United States of America, and a resident of Chicago, county of Cook, 5 and State of Illinois, have invented certain new and useful Improvements in Excavator-Tractors, of which the following is a specification.

This invention relates to mechanism for 10 propelling heavy machinery, such as excavating machines and derricks, over rough or soft ground.

The main objects of the invention are to provide traction mechanism of this nature 15 having many times the surface engagement with the ground possible with wheels but operating on a similar principle; to provide traction mechanism including rotating wheel sectors and shoes or auxiliary bases 20 for said wheel sectors adapted to cooperate with a separate supporting base and having connections for being moved horizontally in the direction of travel of the machine while the weight of the machine is on said sup- 25 porting base; to provide traction mechanism for heavy machinery with substantially flat shoes and means adapted to roll on said shoes to propel the machine and whereby the said shoes are provided with connections to 30 the machine adapted to move the shoes horizontally over the surface of the ground while the said means are disengaged therefrom.

Further objects of the invention are to 35 improve existing mechanism of this nature adapted to propel heavy machinery by a walking or step by step movement by providing means for considerably increasing the amount of horizontal travel with respect 40 to the up and down movements of the machines for each step taken.

An illustrative embodiment of this invention is shown in the accompanying drawings in which—

45 Figure 1 is a side elevation of an excavating machine provided with traction mechanism showing the traction mechanism as it appears when in contact with the ground while propelling the machine. Fig. 2 is a fragmentary side elevation 50 showing the traction mechanism at rest in its normal position. Fig. 3 is a plan view of one of the wheel sectors and its co- operating shoe or auxiliary base. Fig. 4 is a plan view of the device with some of the 55 parts omitted.

The present invention is applicable to a wide variety of heavy portable machines or transporting devices, gun carriages, etc., for the purpose of propelling such devices over 60 soft and uneven ground surfaces. It is an improvement of excavating tractors shown and described in applicant's copending applications for patent, Serial No. 756,473, filed March 24, 1913, and Serial No. 758,160, 65 filed April 1, 1913. Each of said applications relates to an excavating mechanism rotatably mounted on a horizontally disposed circular base together with rotating members and co-operating auxiliary bases 70 adapted to propel such and similar machines forward by a step by step motion. Both of said applications for patent relate to propelling mechanism operating to propel their respective machines by step or arc move- 75 ments around some fixed point in contact with the ground. In the present case the machine is propelled by giving it vertical movements combined with a considerable extent of purely horizontal movement while 80 its supporting wheel sectors roll on their respective shoes or auxiliary bases in contradistinction to being fulcrumed thereon. In all of these different types of propelling mechanisms the main supporting base or 85 turntable of the machine may be permitted to drag over the earth at one side and thus assist in supporting steadyng the machine while it is being propelled, or may be lifted entirely clear of the ground during such 90 propelling movement. This depends upon the particular location of the propelling mechanism with respect to the center of gravity of the machine, or whether or not a plurality of such propelling mechanisms are 95 employed in connection with one machine. The present device is also distinguishable over prior devices in that the auxiliary bases or shoes are maintained in a substantially horizontal position at all times and moved 100 both vertically and horizontally through connections with the co-operating wheel sectors. The present invention results in a considerable decrease in the difficulty and loss of time in the matter of transporting land 105 dredges, steam shovels, and other similar

machines in connection with the working of said machines.

Referring to the drawings, the invention is shown by way of example, in combination 5 with a land dredge of well known design. This dredge is rotatably mounted on a base or turntable 1 by a center bearing 2 and wheels 3 journaled on supports secured to the under side of a platform 4 and co-operating 10 with a circular track 5 secured to base 1. The platform 4 supports the necessary motor or engine and machinery for driving the operating mechanism of the dredge. Said driving mechanism is, as usual, inclosed in 15 a suitable housing 6. In Fig. 1 a mast 7 is shown extending upwardly through the roof of said housing and its upper end supports a sheave 8, the latter being part of a tackle for raising and lowering the drag bucket 20 supporting boom 9. A boom line 10 leading from a suitable controlling drum within the housing passes over the sheave 8 and a sheave 11 and again around sheave 8 having its ends secured to sheave 11. A link 12 25 connects sheave 11 with the end of boom 9. At the end of boom 9 there is secured a bucket hoisting line 13. This line passes around a sheave 14 on the bucket 15 and a sheave 16 on boom 9, and from there into the 30 housing to its controlling power driven drum. The cable for dragging bucket 15 in its digging operation is designated by numeral 17. In the digging operation the necessary transverse swinging of boom 9 is 35 accomplished by swinging the platform 4 and mechanism supported thereon around its bearing connection 2 with the base or turntable 1.

Suitable connections are provided for 40 driving, as required, a shaft 18 journaled in bearings 43 on the platform 4. A clutch connection 35 whereby shaft 18 may be connected to the operating motor 36 is shown in Fig. 4 of the drawings. This motor, as 45 usual on this type of machine, has connections (not shown) for rotating the main body part of the machine upon its platform 1 as required in the operation of digging. By means of the clutch 35 the drive shaft 50 37 of the machine may be clutched to a beveled gear 38 journaled on the shaft and in mesh with a beveled gear 39 fast to a worm shaft 40. The latter carries a worm 41 meshing with a worm wheel 42 fast to 55 shaft 18. The shaft 18 operates and supports the traction mechanism to which the present invention has direct relation. At each end of this shaft which overhangs the 60 sides of the turntable 1 there is rigidly secured a cam 19, which may be in the form of a wheel or sector. The outer edge 20 of this cam is circular with respect to center of shaft 18 through the greater part of its length. But as this edge approaches the 65 straight sides 21 of sectors 19 it is sloped

inwardly toward shaft 18. The sectors 19 are designed in this way in order that in operation when shaft 18 is rotating the corners 22 of the sectors by engagement with co-operating or auxiliary bases 23 will, with an easy movement, first lift the entire machine, including base 1, more or less clear of the ground, and then cause the machine to travel forward by the sectors rolling on said shoes 23. Then as the opposite corners 24 75 of the sectors arrive in the engaging position with shoes 23 the entire machine, together with its platform 1, is again gradually lowered into contact with the ground, platform 1 finally supporting the machine 80 while the sectors 19 return to the position shown in Fig. 2, or again come into contact with the shoes 23 in the further operation of the traction mechanism.

The shoes or auxiliary bases 23 are hung 85 from their respective wheel sectors 19 by cables 25. The latter are secured to eyes 26 in the corners of the shoes 23, and at their opposite ends are provided with hooks 27 by which they are secured to horizontally 90 disposed levers 28 having rings or eyes 29 for this purpose at their ends. The levers 28 are pivoted midway between their ends by pins or pivots 30 to the sectors 19. The pivots 30 are preferably located near to the 95 outer edge 20 of the sectors 19 in order that upon rotation of the sectors the shoes 23 will be given the required horizontal movement with respect to the ground so as to provide for the relative rolling of sectors 19 when the shoes are in contact with the ground. The cables 25 are preferably 100 of such length that the auxiliary bases 23 will contact with the ground when pivot pins 30 are in the same horizontal plane 105 with shaft 18. Thus the auxiliary bases are caused to make arc shaped steps without any lost motion. If necessary the shoes 23 may be provided with teeth or shoulders 110 32 to prevent slipping between the sectors and their shoes, during the rolling action of the sectors when propelling the machine over the ground. During the lifting action of the sectors, previous to their engagement with shoulders 32, they slip with respect to 115 the auxiliary bases 23, in this manner lifting vertically one end of the machine and its base clear of the ground. The weight is preferably so distributed that the rear edge of the base remains in contact with the ground and assists in steadyng and supporting the machine during its traveling movement over the ground.

In the operation of propelling a machine 120 over the ground, rotation of the sectors 19 results in an up and down movement of shoes 23 combined with a horizontal movement of the shoes. Lever 28 remains in a substantially horizontal position during the 125 operation, as its pivot 30 allows the sectors 130

to rotate relatively of the levers 28. Starting with the device in the position as shown in Fig. 2, rotation of sectors 19 in the direction indicated by arrow 31 results in pivot 30 being carried forward of shaft 18 and thereby causing the shoes 23 to swing in a forward direction. The continued movement of the sectors results in the shoes contacting with the ground in their forward position and the cables 25 becoming slack, so that the position of shoes 23 is not disturbed while sectors 19 are in contact therewith. When the sloping parts 22 of the sectors are in contact with the shoes 23 one end 15 of the machine and its support 1 are lifted more or less clear of the ground. During the lifting action of the sectors the latter slip with respect to the auxiliary bases lifting the machine vertically. In this manner 20 the forward end of the base is lifted out of any depression formed and into which the base may have sunk during the dredging operation. Then, when the surfaces 20 of the sectors coöperate with the shoes 23 by 25 rolling thereon, the entire machine will be carried forward in a horizontal direction by the rolling of the sectors, the movement being transmitted from the sectors to the machine by causing horizontal bodily movement of shaft 18 in the required direction. The continued rotation of the sectors results in permitting the machine and its turntable 1 to again gradually come to rest on the ground because of the inward slope of 30 the parts 24 of the surfaces of sectors or cams 19. This operation, of course, may be continued if it is desired to cause the machine to move any great extent at one time, but in practice it is possible that the machine may be moved only a short distance 35 at each operation of the traction mechanism, and possibly between time intervals of considerable length.

It may happen that the machine is swung 40 horizontally on its pivots a great many times during its work and between the operations of the traction mechanism, and at such times it may be desirable to detach the shoes 23 from the machine in order to avoid 45 the needless swinging of said shoes. It may be seen that the hooks 27 will thus permit the machine to be swung independently of shoes 23.

In the peculiar operation of the present 50 device, the machine is tilted to lift its forward end out of any depression which may have been formed in the ground by the weight and vibration during work of the machine. It also enables it to easily pass 55 over normal obstructions in its path. These machines have bases which afford considerable contact with the surface of the ground, the bottom of the base usually consisting of heavy steel plates. With such a construction, if the machine is resting upon

wet clay or earth, by tilting the machine when it is lifted for the purpose of propelling it over the ground, the effect of an enormous suction between the ground and platform 1 is avoided, whereas, if the machine were lifted vertically while maintained in a horizontal position, to overcome the suction would require considerable power, which in the present case may be devoted to purely tractive purposes. 75

It may be seen that this invention may be readily adapted to machines not having the turntable and will admit of such modification that by employing a plurality of pairs of sector wheels 19 with corresponding shoes 23, it is possible to move the machine over the ground by a rolling action of the sectors on their shoes without giving the machine any up and down movement, except according to the irregularities in the surface 80 of the ground, as such pairs of sectors might be set at different relative angles on their respective shafts. Therefore while one pair of sectors would be supporting and propelling the machine forward in a horizontal direction, other sectors could be performing their operation of shifting in a horizontal direction, or lifting and lowering their respective shoes 23. In this manner there would be substantially no up and down movement of the machine necessary except possibly a hardly noticeable movement when the weight of the machine is shifted from one pair of shoes to another. 85 90 95

Although but one specific embodiment of this invention has been herein shown and described, it will be understood that numerous details of the construction shown may be altered or omitted without departing from the spirit of this invention as defined by the following claims. 100 105

I claim:—

1. In a machine of the class described, the combination of a base, a body rotatably mounted thereon, and propelling mechanism carried by said body and adapted to first lift the machine and then cause it to travel over the ground, said propelling mechanism comprising a wheel sector and a coöperating auxiliary base carried by the wheel sector. 110 115

2. The combination with a body and a base therefor, of a wheel sector rotatably connected to said body, a lever pivoted to said sector, an auxiliary base having connections to said lever whereby said lever and base remain substantially horizontal during rotation of the wheel sector but are raised and lowered thereby and said auxiliary base is given a horizontal movement for the purpose of coöperating with said sector in moving the body over the ground. 120 125

3. The combination with a body and a base therefor, of a wheel sector rotatably connected to said body, a lever pivoted to said sector, an auxiliary base having con- 130

- nections to said lever whereby said lever and base remain substantially horizontal during rotation of the wheel sector but are raised and lowered thereby and said auxiliary base 5 is given a horizontal movement for the purpose of coöperating with said sector in moving the machine over the ground, said connections permitting detachment of said auxiliary base from said wheel sector.
- 10 4. The combination of operating mechanism, a base therefor, of a wheel sector rotatably connected to said operating mechanism, an auxiliary base coöperating with said wheel sector and connected therewith 15 to be moved horizontally over the ground, said auxiliary base being provided with a shoulder to limit slipping between said auxiliary base and said wheel sector.
- 15 5. In a machine of the class described, the combination of a supporting base having extended bearing area, a wheel sector rotatably mounted thereon and adapted to tilt said base and drag the same along the ground.
- 20 6. In a machine of the class described, the combination of a supporting base having extended bearing area, a rotatable member mounted thereon and adapted to first tilt said base and then drag the same along the ground.
- 25 7. In a machine of the class described, the combination with a supporting base and body mounted on said base to rotate in a horizontal plane, a wheel sector rotatably mounted on said body and adapted to lift the body and its base and propel the same over the ground, and an auxiliary base carried by said wheel sector and coöperating therewith for the purpose of supporting the machine while it is being propelled over the 30 ground.
- 30 8. In a machine of the class described, the combination with a supporting base and body mounted on said base to rotate in a horizontal plane, a wheel sector rotatably mounted on said body and adapted to lift the body and its base and propel the same over the ground, and an auxiliary base carried by said wheel sector and coöperating therewith for the purpose of supporting the machine while it is being propelled over the 35 ground, said wheel sector being so formed as to gradually lift the machine while slipping on said auxiliary base and then to propel the machine over the ground by rolling 40 on said auxiliary base.
- 40 9. In a machine of the class described, the combination with a supporting base and body mounted on said base to rotate in a horizontal plane, a wheel sector rotatably mounted on said body and adapted to lift the body and its base and propel the same over the ground, and an auxiliary base carried by said wheel sector and coöperating therewith for the purpose of supporting the machine while it is being propelled over the 45 ground, the wheel sector being so formed as to gradually lift the machine while slipping on said auxiliary base and then to propel the machine over the ground by rolling 50 on said auxiliary base.
- 50 10. In a machine of the class described, the combination of a supporting base being so formed as to gradually lift the machine while slipping on said auxiliary base and then to propel the machine over the ground by rolling 55 on said auxiliary base, said wheel sector being so formed as to gradually lift the machine while slipping on said auxiliary base and then to propel the machine over the ground by rolling 60 on said auxiliary base.
- 60 11. In a machine of the class described, the combination of a supporting base being so formed as to gradually lift the machine while slipping on said auxiliary base and then to propel the machine over the ground by rolling 65 on said auxiliary base, said wheel sector being so formed as to gradually lift the machine while slipping on said auxiliary base and then to propel the machine over the ground.
- 65 12. In a machine of the class described, the combination of a supporting base being so formed as to gradually lift the machine while slipping on said auxiliary base and then to propel the machine over the ground by rolling 70 on said auxiliary base and finally permitting the machine and its supporting base to gradually come to rest on the ground.
- 70 13. In a machine of the class described, the combination of a supporting base and body supported on said base to rotate in a horizontal plane, a wheel sector rotatably mounted on said body and adapted to propel the said body and its supporting base over the ground, and an auxiliary base carried by said wheel sector, said wheel sector 75 and auxiliary base coöperating to lift the machine before the propelling movement and to lower it after the propelling movement.
- 75 14. In a machine of the class described, the combination of a supporting base having extended bearing area, operating mechanism mounted thereon and adapted to first tilt said base and then drag the same along the ground.
- 80 15. In a machine of the class described, the combination of a supporting base having extended bearing area, operating mechanism mounted thereon and adapted to first tilt said base and then drag the same along the ground.
- 85 16. In a machine of the class described, the combination of a supporting base having extended bearing area, a body rotatably mounted thereon, and propelling mechanism carried on said body and adapted to cause the machine to travel forward while raising one side of said base from the ground and permitting the opposite side to drag.
- 90 17. In a machine of the class described, the combination of a base having extended bearing area, a body rotatably mounted on said base, and supporting a motor, and propelling mechanism driven by said motor and mounted on said body and adapted to cause the machine to travel forward while raising one 95 side of the base and permitting the opposite side to drag over the earth and thereby steady the machine in its movement.
- 95 18. In a machine of the class described, the combination of a base having extended bearing area, a body mounted to rotate horizontally thereon, a horizontally disposed shaft movable with said body and propelling mechanism actuated by said shaft arranged to lift one side of said base while the opposite side is permitted to drag over the earth.
- 100 19. In a machine of the class described, the combination of a base, a body rotatably mounted thereon, a horizontally disposed shaft movable with said body, means for 105

rotating said shaft, arms rigidly secured to the ends of said shaft and supporting at each side of said body a foot at such distance from the shaft that when the latter is 5 rotated the feet will engage the ground, lifting the machine and propelling it forward, the center of gravity of said machine being so located that one side of said base will

drag over the earth when the machine is being propelled.

Signed at Chicago this 2nd day of April, 1913.
